UNITED STATES PATENT OFFICE.

GARRETT W. HENRICKS, OF INDIANAPOLIS, INDIANA, ASSIGNOR OF TWO-THIRDS TO
GEORGE F. KREITLEIN, OF INDIANAPOLIS, INDIANA.

LIQUID-CONTAINER.

1,282,575.

Specification of Letters Patent. Patented Oct. 22, 1918.

Application filed March 21, 1917. Serial No. 156,463.

To all whom it may concern:

Be it known that I, GARRETT W. HENRICKS, a citizen of the United States, and a resident of Indianapolis, county of Marion 5 and State of Indiana, have invented a certain new and useful Liquid-Container; and I do hereby declare that the following is a full, clear, and exact description thereof, reference being had to the accompanying 10 drawings, in which like letters refer to like parts.

This invention relates to a liquid container particularly for oil or gasoline, where it is necessary to carry the same in an automobile or to pour it into small oil openings 15 difficult of access without the need of a funnel.

The chief feature of the invention consists in providing the can or container with 20 a disappearing spout, said spout having a side opening or port near its inner end and being opened or closed by a substantially stationary plunger in the spout relative to which the spout is slidable to bring 25 the port in front of or to the rear of the plunger.

Another feature of the invention consists in providing a port substantially V-shaped in its side so that, in coöperation 30 with the plunger, the extent of flow of oil or the like may be easily controlled or regulated.

The full nature of the invention will be understood from the accompanying drawings 35 and the following description and claims:

In the drawings, Figure 1 shows a perspective view of the liquid container with the spout in closed position. Fig. 2 is an 40 enlarged view of a cross section taken on the line 2-2 of Fig. 1, with a portion of the spout in elevation. Fig. 3 is a side elevation of the can in pouring position. Fig. 4 is a perspective view of the spout in 45 open position with a portion thereof in cross section. Fig. 5 is the same as Fig. 4 showing the spout in closed position. Fig. 6 is the same as Fig. 4 showing the spout adjusted for pouring a thin stream.

There is shown in the drawings herein a 50 liquid container 10 having a folding handle 11 hinged to the top thereof and being provided at one end with a depression 12.

Extending diagonally through the depression 55 12 in the center of the upper central

end of the container there is a spout 13 of the ordinary construction excepting that it is tubular and has the same diameter throughout its entire length, with a curved and reduced portion on its outer end. Said 60 spout is held slidably in place by the partition 14 of the depression 12 and a cap 15 which is adapted to screw down on a felt washer 16 so that the liquid is prevented from escaping around the surface of the 65 spout, and the oil on its surface will be wiped off by the felt washer 16. Secured to the container on the inside thereof there is a rod 17 provided with a plunger 18 at its upper end. Said rod is rigidly secured to 70 the can in such a position that it will extend longitudinally through the tubular spout 13, and the plunger 18 will fit snugly therein so that the spout may slide back and forth thereon. Near the lower end of the spout 75 there is provided a port or opening 19 cut at an angle in the side of the spout, as shown in the drawings. When the opening 19 is below the plunger 18, the spout will be closed to prevent the flow of liquid therethrough, as 80 shown in Figs. 2 and 5, while the liquid may pass through said port or opening in the spout 13 when the spout is in the position shown in Fig. 4. To open the spout and permit the liquid to flow therethrough, it must be withdrawn from the can until the opening 19 is between the partition 14 and the plunger 85 18. As the spout is gradually pushed back, the opening 19 will be decreased owing to its passing over the plunger 18 so that the flow 90 of liquid may be controlled, as shown in Fig. 6.

It may, therefore, be readily seen that the flow of liquid may be cut off by a slight longitudinal movement of the spout, and by 95 manipulating it properly, the flow may be controlled.

At the rear of the can and located on its upper side, there is a filling port 20 in which is screwed a depressed cap 21 for closing it. 100 The cap 21 is provided with a handle 22 which extends upwardly therefrom flush with the upper surface of the can so that it may be screwed in and out thereof. There is an air vent 23 in the upper portion of the cap and an air vent 24 through the lower portion through which air may be drawn into the can as the liquid is poured out. For closing the air vent 24 when the can is in normal position, there is provided a 105 110

ball 25 which will roll out of engagement with said air vent and open it when the can is turned in position to pour the liquid and will return and seat itself in said air vent 5 when the can is returned to normal position, as shown in Fig. 2. By means of this construction air is automatically supplied to the interior of the can when necessary, and shut off so as to prevent evaporation when 10 not in use. This type of cap is especially adapted to be used with evaporating liquids, but under ordinary circumstances any other type of cap may be used. By using the ordinary type of cap the can may be turned up- 15 side down without leaking its contents.

The employment of the plunger or piston 18 on the outer end of the rod 17 to operate inside the spout and serve as a valve to open and close the spout, as it is moved out or in, 20 enables the spout, when in its outer position to permit an unobstructed flow of the fluid through it, and the outlet can be closed while the can is still in a tilted or discharging position, by moving the can forward on the 25 spout, for instance while putting oil in a gasolene engine, and when the spout is in its inner position the plunger will extend well toward the outer end of the spout and clear it of the oil or other fluid.

30 The invention claimed is:

1. A liquid container having an opening therein, a disappearing spout slideable longitudinally back and forth through said opening and with a port in its side wall, and a 35 substantially stationary plunger within the spout, and relative to which the spout is slideable to bring the port in front or to the rear of the plunger for opening and closing the spout.

40 2. A liquid container including a can having an opening therein, a disappearing spout

adapted to slide longitudinally back and forth through said opening so that it may be telescoped within said can or withdrawn therefrom, and having a substantially V-shaped tapered port near the inner end of said spout and a non-slidable closure in said spout whereby the port is adapted to be opened and closed by the longitudinal movement of the spout for controlling and regulating the flow of liquid therethrough. 45

3. A liquid container including a can having an opening therein, a disappearing spout adapted to slide longitudinally back and forth through said opening so that it 55 may be telescoped within said can or withdrawn therefrom and having an opening near the inner end thereof, and a rod stationary in said can having a plunger within the spout relative to which the spout slides whereby the position of the plunger relative to said opening will open or close said spout and regulate the amount of fluid passing through the spout. 60

4. A liquid container including a can having an opening therein, a disappearing spout adapted to slide longitudinally back and forth through said opening so that it may be telescoped within said can or withdrawn therefrom, and having a substantially V-shaped tapered opening near the inner end thereof, and a rod fixed to said can having a plunger on the end thereof and within the spout so as to vary the area of said opening as the spout is withdrawn, whereby the flow 75 of liquid therethrough may be controlled by the movement of said spout relative to said plunger.

In witness whereof, I have hereunto affixed my signature.

GARRETT W. HENRICKS.
